APPARATUS FOR SEPARATING OXYGEN
FROM AIR AND DELIVERING THE OXY-
GEN UNDER PRESSURE

Adolf Messer, Frankfort-on-the-Main, Germany

Application October 17, 1936, Serial No. 106,166
In Germany September 4, 1936

4 Claims. (Cl. 62—122)

For drawing the separated liquid oxygen under low pressure from an air separating plant and delivering it to a high pressure, for instance through an evaporating coil, a pump of the 5 plunger type immersed in a body of liquid oxygen collected in a portion of the separating apparatus, is not satisfactory. The heat produced by the sliding friction of the plunger along the cylinder walls, and the vacuum produced in 10 the cylinder, give rise to fractional evaporation or distillation of the liquid oxygen in the cylinder and impairs the efficiency.

To cool down the liquid oxygen to avoid any 15 evaporation in the pump cylinder while the liquid oxygen is being drawn into the pump, is a very expensive and complicated process.

One object of the present invention is to provide an apparatus which is efficient in operation and does not have the disadvantages above referred to.

In carrying out the present invention in its preferred form, there is provided a slow running gear pump for raising the liquid oxygen against pressure. This gear pump has no sliding parts which will create sufficient friction 25 to evaporate the liquid oxygen, and creates no vacuum which might impair the efficient operation of the pump.

As a feature of the present invention, the main 30 drive shaft of the gear pump is inclined upwardly from the pump with respect to the horizontal, and the stuffing box for the main drive shaft and the driving motor are disposed in the relatively warm outside atmosphere. This inclination of the main drive shaft is preferably 35 such that the stuffing box will be near the maximum level of the liquid oxygen in the air separating column, so that there is little or no pressure of the liquid oxygen acting on said stuffing box. Furthermore, by providing an inclined 40 shaft, any liquid oxygen evaporated along the shaft will rise to the level of the stuffing box and will act somewhat as an insulation against heat conduction from the outside atmosphere, 45 and prevent the inflow of further liquid oxygen.

As a further feature, there is provided a variable speed transmission between the motor and the drive shaft, whereby the speed of the pump may be regulated in accordance with the quantity 50 and pressure desired in the liquid oxygen.

Since the motor, the variable speed transmission, and the stuffing box for the main drive shaft, are disposed away from the cold region of the separating apparatus and in the warm 55 outside atmosphere, the lubricating agents there-

on will not be cooled sufficiently to impair the function of these pump operating members.

In the accompanying drawing, there is shown for the purpose of illustration, one form of air separating apparatus embodying the present 5 invention.

In this drawing there is shown a column 10 having a heat interchanger 11 at the upper end, and a rectifying section 12 at the lower end. Air under pressure is delivered through a coil 13 of the heat interchanger 11 where it passes in countercurrent heat interchange relationship with the outflowing nitrogen and a coil 14 in which the evaporation of the separated liquid oxygen takes place. The precooled air leaving 15 the interchanger 11 goes through a coil 15 at the bottom of the column 10 through an expansion valve 16, and is delivered at the upper end 20 of a series of trays 17 in the rectifying section 12 of the column. By this operation, as the 25 resulting liquefied air trickles downwardly over the trays 17, it is separated into the liquid oxygen which collects at the bottom of the column 10, and gaseous nitrogen which passes around the coils of the heat interchanger 11 and out through 30 an outlet 18. The coil 14 is provided with a valved outlet 19 which delivers the separated 35 evaporated oxygen to a suitable storage tank at a substantial pressure controlled by the adjustment of the valve 20 in said outlet, without 40 the necessity of compressing said evaporated oxygen.

As a feature of the present invention, the liquid oxygen collected at the bottom of column 10 is delivered to the inlet end of the coil 14 in the heat 35 interchanger 11 through a gear pump 21 having an inlet 22 and an outlet 23, the two gear members of the pump being operated at low speed 40 through a gear arrangement, such as a worm and worm wheel, from a main drive shaft 24. This shaft 24 is encircled by a tubing or sheathing 45 which slants upwardly and outwardly as shown.

The shaft 24 is operated from an electric motor 26 and the speed of rotation of said shaft is controlled by a variable speed transmission 28 which may be adjusted by a suitable control handle 30. The shaft 24 is supported by a bearing which is mounted outside the cold region of the separating apparatus so as to be in contact with the warm 50 outside air, said bearing comprising or including a stuffing box 32 to prevent leakage of oxygen therethrough. The stuffing box and the shaft 24 are preferably so arranged that the stuffing box 55 will be at substantially the maximum level of the 60

liquid oxygen in the bottom of the column 18, so that the liquid oxygen in the tubing 25 acts with little or no pressure on said stuffing box. Furthermore, by means of this arrangement, any 5 evaporated oxygen will rise along the shaft 24 and be trapped at the upper end thereof so as to serve as a heat insulation to prevent the conduction of heat into the main body of the liquid oxygen and prevent liquid oxygen from flowing up to 10 the stuffing box.

Having thus described my invention, what I claim as new and desire to secure by Letters Patent is:—

- 15 1. An apparatus for separating oxygen from air, which includes a rectification column in the bottom of which the liquid oxygen separates and collects, a liquid oxygen evaporating coil, a pump in the bottom of said column for forcing the separated liquid oxygen through said evaporating 20 coil, and having a drive shaft extending to the exterior of the apparatus, a casing encircling said shaft, and a stuffing box disposed at the outer end of said casing outside the cold region of the column and in the warmer outside atmosphere.
- 25 2. An apparatus for separating oxygen from air, which includes a rectification column in the bottom of which the liquid oxygen separates and collects, a liquid oxygen evaporating coil, a pump in the bottom of said column for forcing the separated liquid oxygen through said evaporating 30

coil, and a main drive shaft for driving said pump and slanting upwardly and outwardly from the latter.

3. An apparatus for separating oxygen from air, which includes a rectification column in the 5 bottom of which the liquid oxygen separates and collects, a liquid oxygen evaporating coil, a gear pump in the bottom of said column for forcing the separated liquid oxygen through said evaporating coil, a main drive shaft for driving said 10 gear pump and slanting upwardly and outwardly from the latter, a motor for driving said shaft, and a stuffing box for said main drive shaft, said motor and said stuffing box being disposed outside 15 of the cold region of the column and in the warmer outside atmosphere.

4. An apparatus for separating oxygen from air, which includes a rectification column in the bottom of which the oxygen separates in liquid 20 form, a heat interchanger including an oxygen evaporating coil having an outlet leading to a storage holder, a rotary pump at the bottom of said column for forcing the separated liquid oxygen through said evaporating coil, a shaft 25 extending upwardly and outwardly from said pump, a tubular casing encircling said shaft and open at the lower end, and a stuffing box at the outer upper end for trapping gaseous oxygen in said casing.
